UNITED STATES PATENT OFFICE.

CHARLES H. ROBERTS, OF EVANSVILLE, INDIANA.

IMPROVEMENT IN FIRE-PLUGS AND HYDRANTS.

Specification forming part of Letters Patent No. **154,087**, dated August 11, 1874; application filed June 1, 1874.

To all whom it may concern:

Be it known that I, CHARLES H. ROBERTS, of Evansville, Vanderburg county, Indiana, have invented certain Improvements in Fire-Plugs and Street-Hydrants, of which the following is a specification:

My invention relates to that class of fire-plugs in which a supplementary valve may be adjusted to cut off the water when the ordinary valve is to be repaired; my improvements consisting in providing the valve-casing of the fire-plug B with a detachable plate, F, having seats for both valves, and recessed to permit the escape of waste water, and in guiding the stem of one valve by that of the other, all as shown in sectional elevation in the accompanying drawing.

The casing of the fire-plug consists, in the present instance, of three flanged sections, a, b, and c, bolted together as shown, the water-inlet d being in the lower section, and the outlet e in the upper section. The plate F is clamped between the sections a and b of the casing, and on the under surface of this plate, which has a central opening or openings for the upward passage of the water, is formed a seat, h, for the usual supplemental valve A, and on its upper surface a seat, i, for the valve D. The said plate has also, on its upper side, a tubular projection, E, with lateral openings k, which constitute the above-mentioned waste outlet, a portion, j, of the valve D encircling this tubular projection, so that when the said valve is raised from its seat it will close the openings k, and thus prevent escape of water, while when the valve D is lowered it will uncover the said openings k, and thus permit the waste water to pass off from the interior of the plug through the outlet E. When the valve D or other portion of the interior of the plug need repairing, the valve A is raised to its seat h, in order to turn off the water, as indicated by dotted lines, this adjustment being effected by turning the screw-spindle I, which is adapted to an internal screw-thread cut in the plate F. The spindle I is turned by a key adapted to its

squared upper end, and passed down through a tubular stem, H, after removing the screw-cap x, of the latter. When the valve A is to be repaired, the water is shut off from the plug, and the plate F detached with the valve, free access to which is thus obtained. The valve D, which is the one ordinarily used by firemen and others, has a tubular projection, l, with an external screw-thread, to which is adapted an internal thread in the above-mentioned hollow stem H, so that on turning the latter the valve can be raised or lowered, being guided by the stem I of the valve A. A leather or other washer, m, is interposed between a flange on the stem H and the top of the plug, to prevent leakage at the latter point, and the said stem has an enlargement, p, at the top, provided with wrought-metal pins, q, which permits it to be operated, in turning the water on and off, by an ordinary hose-spanner.

My improvements are applicable to street-hydrants as well as to fire-plugs.

I claim as my invention—

1. The combination, with the sectional casing of a hydrant or fire-plug, of a plate, F, confined between the sections, having seats for the valves A D, an opening, E, for the passage of waste water, and constituting the sole support of the valves, valve-rods, and their appliances, all as described.

2. The combination of the valve-plate F, its tubular projection and outlet, and the valve D having a tubular sleeve, j, inclosing and sliding on said projection, as set forth.

3. The combination of the valve D, its tubular stem l, and the valve A having a stem, I, extending into and guiding the valve-stem l, as set forth.

In testimony whereof I have signed my name to this specification in the presence of two subscribing witnesses.

CHAS. H. ROBERTS.
